(57) **CLAIM**

We claim the ornamental design for a reflector for a lighting fixture, as shown and described.

DESCRIPTION

FIG. 1 is a bottom perspective view of the reflector for a lighting fixture of the claimed design;

FIG. 2 is a side view thereof;

FIG. 3 is a front view thereof;

FIG. 4 is a rear view thereof;

FIG. 5 is a top view thereof; and,

FIG. 6 is a bottom view thereof.

The ornamental design which is claimed is shown in solid lines in the figures. The broken lines in the figures illustrate portions of the reflector for a lighting fixture which form no part of the claimed design. The break in the middle of the design indicates that the claimed design is of no specific length.
